IMPROVED ROLL FOR FELTING OR SIZING HAT BODIES BY MACHINERY.

PHILIP W. SOMERS, OF DANBURY, CONNECTICUT.

Letters Patent No. 60,275, dated December 4, 1866.

SPECIFICATION.

TO ALL WHOM IT MAY CONCERN:

Be it known that I, PHILIP W. SOMERS, of Danbury, in the county of Fairfield, and State of Connecticut, have invented a certain new and improved Roll for Felting or Sizing in Hat Bodies in the roll, by Machinery; and I do hereby declare that the following is a full and correct description thereof, reference being had to the annexed drawings, making a part of this specification, and to the letters of reference thereon.

My said invention consists in an improved roll, in which the coils or folds of the bat or bats, rolled up within the covering cloth, are in a reverse direction from the coils or folds of the covering or enveloping cloth. Hitherto rolls have been made up for machines the same as for the hand process of sizing; that is, the coils of the rolled bats or bodies within the enveloping cloth run in the same direction as the coils of the enveloping cloth, and, although machines of various kinds have been devised to work the rolls for the purpose of sizing them in, they have hitherto failed to take the place of the hand-working, for the reason that the bodies thus rolled and worked do not shrink in the direction designed by the hatter when making up his roll; and also, because they are inferior in quality to the hand-worked bodies. But in the use of my improved roll, above described, these difficulties do not occur, and hat bodies can be practically sized in, by working them in the roll, in machines which carry the roll or rolls continuously forward, either by a simple rolling motion, or by a compound forward motion having a jiggling action involved with it, as in most machines heretofore patented. I have no certain knowledge of the reason why reversing the direction of the coils of the rolled bodies with respect to the coils of the covering cloth produces so great a difference in the result of the operation of machinery upon the fibres of the bats constituting the hat bodies, but believe that when the bodies are submitted to the action of machinery in my improved roll, the fibres receive motion and pressure in the same direction as they do when subjected to the hand process in the form of rolls commonly used. I have observed that when a hat body in the roll with the enveloping or working cloth is rolled on a table, under pressure, that the coils work or move in one direction or its opposite, according to the direction in which it is being rolled under pressure. Those acquainted with the operation of machinery used, or attempted to be used, in working hat bodies in the roll in the process of sizing, are familiar with the fact that the rolls have to be put into the machines in such direction that the enveloping cloth will be rolled up and kept rolled up under pressure, otherwise the enveloping or working cloth would be unrolled or stripped from the bats constituting the hat bodies, the machine clogged up, or the bats ruined. Yet this is precisely the opposite direction from that in which motion with pressure is usually applied to the same rolls by the hand process, wherein the motion under pressure, during the greater part of the time, is in a direction away from the hatter, unrolling the covering cloth to the extent of that motion, the roll being restored by the hatter rolling it lightly back towards him; it being a necessity in the operation of continuous machines on hat bodies in the roll to keep rolling the rolls under pressure in a direction that will keep the covering cloth of the rolls rolled up, which is the contrary direction from the direction in which the greatest pressure and motion are applied by hand. I have sought to remedy the difficulties experienced in working rolls by machinery by reversing the direction of the coils of the bats within the covering or felting cloth, with respect to the covering cloth, and by this means I am enabled to keep the rolls rolled up in the machine, and yet get the good result of hand sizing. My new roll may be most conveniently made by rolling up the body or bodies toward the hatter, as is usual in making the old roll, and then turning the roll end for end before rolling it up in the enveloping or working cloth, which is then rolled around the roll of bodies in a reverse direction, by rolling towards the hatter as usual; the reversal being effected without other change in the manipulation of the hatter in making the roll than turning the roll of the body or bodies end for end before rolling it up in the cloth. The roll may, however, be made by rolling up the body or bodies towards the hatter on the working cloth, and then rolling the working cloth around the roll of bodies by rolling from the hatter without changing the roll of bodies end for end, as when the roll is made by rolling both the bodies and working cloth towards the hatter. But the latter mode of operation is not in accordance with the usual practice of hatters, which is to roll towards them, and therefore not so convenient.

The drawing, Figure 1, shows an end view of a hat body and covering cloth, rolled for the hand process of sizing, with the coil *a* of the hat body in the same direction as the coils *b* of the working cloth.

An end view of my new reverse roll is shown at Figure 2 of the drawings, the coils *c* of the body being in a reverse direction to the covering cloth *d*.

Although my new roll can be worked to better advantages than the old roll in machines having a vibrating or jiggling motion combined with a forward motion, such machines are not adapted to produce the best results by reason of the reverse rolling they give the roll under pressure, and therefore I have devised certain improvements in machinery for working my new rolls, embodied in a machine described in a separate application for Letters Patent, which is not suitable for working the old roll.

I claim, as my invention and improvement—

The new roll adopted for working hat bodies in the roll by machinery, wherein the coils or folds of the body or bodies rolled up within the covering cloth are in a reverse direction from the coils or folds of the covering cloth, substantially as and for the purposes hereinbefore set forth.

PHILIP W. SOMERS.
